Patented Apr. 4, 1922.

UNITED STATES PATENT OFFICE.

CARL C. MYGIND, OF KANSAS CITY, MISSOURI.

AMUSEMENT DEVICE.

1,411,451.

Specification of Letters Patent. Patented Apr. 4, 1922.

Application filed February 12, 1920. Serial No. 358,080.

To all whom it may concern:

Be it known that I, CARL C. MYGIND, a subject of the King of Denmark, and a resident of Kansas City, in the county of Jackson, State of Missouri, have invented a certain new and useful Improvement in Amusement Devices, of which the following is a complete specification.

This invention relates to amusement devices and the object is to produce a simple and inexpensive device which can be employed for the amusement of children or adults. Broadly considered the invention consists of a handle provided with a head at one end having guides or zones and a weighted cord attached to the head and adapted to be wound upon or around the head within the zone. To perform this operation requires more or less skill which can be acquired with practice by children as well as by grown folks. The invention contemplates also additional guides marked or formed on the head and suitable rules may be provided whereby the winding or wrapping of the cord around the head within certain zones will count a perfect score which may be any predetermined number, and the wrapping of the cord around other zones will count for less value.

With the object of producing an amusement device which can be employed to great advantage for entertainment purposes, the invention consists in certain novel and peculiar features of construction and organization as hereinafter described and claimed; and in order that it may be fully understood reference is to be had to the accompanying drawing, in which—

Figure 1 is a perspective view of an amusement device embodying one form of the invention;

Figure 2 is a transverse section of the same with the cord wound or wrapped upon the head of the device;

Figure 3 is a fragmentary perspective view of a modified form of the device;

Figure 4 is a fragmentary perspective view of another form of the device;

Figure 5 is a perspective view of still another form of the device;

Figure 6 is a fragmentary perspective view of still another form of the device; and

Figure 7 is a fragmentary perspective view of another form of the device.

In the said drawing, 1 indicates a handle of any suitable size and length, terminating

at one end in a head 2 which is preferably somewhat wider than the handle, and the head is preferably provided centrally with a perforation or hole 3.

A cord 4 of suitable length is passed through said hole and secured at one end so that it cannot slip back through the hole, and at its opposite end is provided with a weight preferably in the form of a rubber ball as shown at 5.

The head will be provided with a central zone within which the player will try by grasping the handle and whirling the device, to wind or coil the cord. There may also be provided at each side of the central zone, secondary zones, which will count for less value when the cord is wound thereon, that is, if one or more convolutions of the cord are wound upon any one or more of the secondary zones the play will not be considered perfect, as it will have less value than if wound upon the central zone. Rules may be provided giving certain fixed values for the winding of the cord upon the central zone and upon the outside zones so that it may be determined what value each manipulation of the device shall have and thus enable one to keep a proper tally or score.

In Figure 3 the head is provided with cross marks 4^a between which the perforation 3 is located. This represents the central or perfect zone.

In Figure 4 the head is provided with outwardly projecting lugs 5^a, in the plane of the perforation 3, and to play the game perfectly with this device the cord will have to be wrapped entirely upon the outer ends of the said lugs and not slip off the same upon the adjacent edges of the head. It is obvious that to wrap cord by whirling the device, completely within the zone represented by the marks or zones 4 and the outer ends of the lugs 5 in Figures 3 and 4 respectively, will require considerable skill or luck.

These forms will perhaps be most appropriate for large children or adults. For smaller children the forms represented by Figures 1, 2, 5, 6, and 7 will perhaps be more appropriate.

In Figures 1, 2, 5, and 7, the central zone is represented by notches 6 formed in the opposite edges of the head in line with the perforation or hole 3, it being noted that in Figure 5, a metallic strap 7 encloses the head and the notches are formed in the pro-

jecting ends of the strap at opposite sides of the head, the said strap having a central hole 8 through which the cord 4 extends.

In Figure 6 the opposite edges of the head are provided with notches 9 flanking the central notches 6 and of considerable less depth by preference than the latter, so that it shall be impossible for more than one or two convolutions of the cord to stay in said shallow notches 9. Opposite notches 9 represent zones of less value than the central notches, the value of the zones diminishing as they become more remote from the central notches.

In Figure 3 corresponding outside zones 10 are shown by transverse lines or marks across the head, and said zones as they re-cede from the central zone are of diminishing value.

In Figure 7 the head is shown as corrugated with a central zone or corrugation 11 of greater depth than the outside or shallower zones or corrugations 12, the latter being of diminishing value, in the same sense that the zones 9 and 10 of Figures 6 and 3 respectively are of diminishing value.

As the method of manipulating the device for playing the game has been explained no recapitulation thereof is believed to be necessary, but it will be apparent that with an amusement device of this character children and even adults can entertain themselves, especially if the game is on a competitive basis.

From the above description it will be apparent that I have produced an amusement device embodying the features of advantage set forth as desirable in the statement of the object of the invention, and which may be modified in various ways without departing from the principle of construction involved.

What I claim is:

1. An amusement device, comprising a handle having a flat head, a cord attached at one end to the head and a weight secured to the free end of the cord; said head being provided with a cord-receiving guide in transverse alinement with the point of attachment of the cord to the head.

2. An amusement device comprising a handle having a flat head and provided in one side edge of the head with a notch, and also provided with a cord attached at one end to said head in the transverse plane of said notch, and provided at its free end with a weight.

3. An amusement device comprising a handle having a flat head having a central perforation and notches at opposite sides of and in transverse alinement with said perforation, and a cord extending through said perforation and secured against slipping through the head, and provided at its free end with a weight.

In witness whereof I hereto affix my signature.

CARL C. MYGIND.
